UNITED STATES PATENT OFFICE

ROBERT HARRIS, OF LONDON, ENGLAND, ASSIGNOR, BY MESNE ASSIGNMENTS, TO
LITHOPRINTEX CORPORATION, A CORPORATION OF DELAWARE

PRESS-FRAME FOR DUPLICATING OR PRINTING APPARATUS

Application filed June 10, 1927, Serial No. 197,789, and in Great Britain August 11, 1926.

This invention relates to press frames for duplicating or printing apparatus, and particularly for photographic step-and-repeat contact-printing machines, of the type comprising a unit-holder for carrying a unit, such as a photographic negative or positive, a base member (which is usually mounted to reciprocate in the machine to bring the printing surfaces into contact), and a supporting member that carries the unit-holder and is movably mounted on the base.

In press frames of this type proposed heretofore all adjustments of the unit in relation to the base member and other associated parts of the machine had to be performed when the unit-holder carrying the unit was in the machine.

This invention has for its main object to provide an improved construction of press frame of the type described which shall obviate the necessity for such adjustments to be made after the unit has been placed in the machine, whereby an appreciable saving in time in the operation of the machine is obtained.

According to an important feature of the invention, there is provided a press frame of the type described, characterized in that the supporting member whereon the unit-holder is adjustably carried, is so mounted on the base member as always to occupy the same position when secured thereon, and to be readily removed therefrom, so that when replaced whilst carrying the unit-holder it takes up automatically its desired setting, for the purpose of enabling the unit to be accurately positioned, for example by means of lay-marks, on the supporting member out of the machine and then securing the supporting member in a predetermined position on the base member in the machine.

According to another feature of the invention, a press frame having clamping means arranged adjustably to secure the unit-holder on the supporting member, is characterized in that the clamping means are so arranged that when slack, but while still carried by one of said members, they permit said unit-holder to be adjusted on the supporting member in two directions lying transversely (e. g.

at right-angles) to one another and also angularly in its own plane in relation to the supporting member. Consequently, if the negative is positioned out of true on the holding member this error can be negatived by corresponding adjustment of the holding member on its support. That is to say, the negative need not be accurately positioned on the negative holder itself.

Conveniently, the clamping means slidably engage one of said members in one direction thereof, and slidably engage the other of said members in a direction transversely, for example at right-angles, to the first said direction.

According to yet another feature of the invention, a press frame as set forth above is characterized in that the base member is arranged slidably to receive and support said supporting member, locating means are arranged for automatically locating said supporting member on the base member in two directions at right-angles to one another independently of its support at the end of its sliding movement into its operative position, and holding means are provided for securing the supporting member on the base member in its located position. By tightening the said holding means the supporting member carrying the unit-holder with the unit positioned on the latter can be automatically positioned in its desired operative setting.

Conveniently, the supporting member is mounted on the base member by two slideways, one at each side of the base, and said locating means are situated between the slideways.

Other features of the invention will be described hereinafter and pointed out in the claims.

One embodiment of the invention is diagrammatically illustrated by way of example in the accompanying drawings, wherein:

Figure 1 is a bottom plan view of a press frame constructed according to the invention for use in a photographic step-and-repeat contact-printing machine, parts of the frame being shown broken away;

Figure 2 is a section taken on the line 2—2 in Figure 1;

Figure 3 is a section taken on the line 3—3 in Figure 1;

5 Figure 4 is a section taken in the line 4—4 in Figure 1;

Figure 5 is a section taken on the line 5—5 in Figure 1, and

10 Figure 6 is a section taken on the line 6—6 in Figure 1.

Figures 2, 3, 4, 5 and 6 are each shown on a scale larger than that of Figure 1.

Like reference numerals designate like parts throughout the several views.

15 Referring to the drawings, a press frame for use in a photographic step-by-step contact-printing machine comprises three principal parts 10, 11, 12, namely, a negative holder 10 referred to above as a unit-holder, 20 a slide or support 11 therefor, referred to above as a supporting member, and a base member 12 which is usually mounted in the machine. Each of these three members is 25 in the form of an oblong frame, approximately equal in size, lying one on another with the slide 11 in the middle, whereof the two shorter sides will be referred to as ends and the two longer ones as sides. When in 30 use the base 12 will usually be uppermost and will transmit pressure to the negative 13 carried on a sheet of glass 114 at the underside of the negative holder, for pressing the negative against a sensitized metal plate.

Each side of the negative holder has in its 35 face adjacent the slide two slots 14 of T-section lying parallel with the ends, the two slots in one side being in line with the two slots in the opposite side and spaced apart equally from the centre line 50 of the holder passing through those sides. The corresponding sides of the slide 11 have adjacent the holder 10 each an inwardly-directed lip 15 and four clamps (Figure 2) are provided, one for each slot, for engaging the lip. Each of these 40 clamps comprises a bolt 16 having its head movable in the cross of a T slot and on the stem of each bolt is an L-shaped plate 17, 18 which can be secured by a nut 19 with one limb 17 bearing against said lip 15 and its 45 other limb 18 against the negative holder 10. By sliding the bolts in said slots and along the lips the negative holder can be adjusted in any direction on the slide according to laymarks, an angular movement of about 5° 50 about the centre of the holder being generally found sufficient for the correction of errors in positioning of the negative on the holder. This adjustment can be effected out of the machine which facilitates its performance.

60 In order to facilitate correctly positioning the holder 10 and slide 11 thus clamped together on to the base member 12 in the machine the slide 11 has various guides and the base member is provided with various stops 65 corresponding thereto, so that when the slide

is slid with the holder on to the base and secured in its end position, the negative will be automatically correctly positioned in the machine. The ends of the slide are provided each with a tongue 20 (Figure 3) of L-section 70 extending from side to side of the slide, which tongues are received each in a corresponding groove 21 in the ends of the base 12. The tongues 20 are a loose fit in the grooves and these tongue-and-groove connections 20, 21 serve as a coarse adjustment of the slide on the base and also for holding these two parts together. In order to position the slide accurately in the direction of length of the slide, i. e., in the direction transverse to its direction of sliding, the slide 11 and base 12 are provided on the centre line 50 at the front and rear sides with two grooves 22, 23 (Figures 1, 4 and 6), one at each side, arranged in line one with the other, and two fine-adjustment tongues 24, 25, one at each side, tapered each at one end, which fit accurately therein, the rear fine-adjustment tongue 24 and groove 22 considered in the direction of sliding into position indicated by the arrow 75 in Figure 1 being wider than the front. As illustrated, the groove 22 is provided on the slide 11, and the tongue 24 on the base 12, whilst the groove 23 is on the base 12 and the tongue 25 is carried by the slide. Alternatively both tongues may be on the slide; owing to their difference in width the front fine-adjustment tongue 25 can readily pass through the rear groove 22 when the holder is being positioned. Obviously both the 80 grooves may be provided on the slide and both the tongues on the base, if desired.

Two stops 26 (Figure 2) for arresting the slide 11 at the end of its forward movement are provided on the base 12, one at each side of the centre line at the front side of the base. These stops 26 are undercut to slant downwards and co-operate with correspondingly chamfered stops 27 fixed on the front side of the slide 11. Two screw clamps 30 (Figure 5) are secured on the rear side of the base, one opposite each of said stops. These clamps comprise each a yoke piece 31 having two jaws, 32, 33, one engaging under a shoulder 34 of a recess 35 in the base, and the other being bevelled and bearing on an outwardly slanting shoulder 36 on the slide 11, so that when held home by a nut 37 on the clamp the yokes 31 not only press the slide 11 home 85 against its stops 26, but also force the opposed faces of the slide and base firmly together in a direction normal to them.

After adjusting the holder 10 and slide 11 so as to carry the negative in its correct position, the same can be assembled in the machine on the base member 12 aforesaid by a simple sliding movement and by a simple clamping movement, when the negative will be automatically correctly positioned in the 90

machine and ready for being shifted step-by-step over the press plate.

The bodies of the frames 10, 11, 12 may conveniently be made of aluminium, whilst the parts subjected to wear, such as the parts 26, 27, 31, 34, 36, 22, 23, 24, 25, are preferably made of a harder material, such as steel.

The invention is not restricted to press frames for contact-printing machines. Also, various modifications may be made in the details of construction as described above without departing from the invention. For example, the number of stops 26 may be increased or decreased, and the form of the tongue-and-groove guides 22, 24 or 23, 25 and clamping devices may be changed.

I claim:

1. A press frame of the character described, comprising in combination a base member, a supporting member detachably mounted on the base member, a unit-holder for carrying a unit adjustably carried by said supporting member, clamping means for clamping said holder in its adjusted position on said supporting member, and holding means for removably securing the supporting member in its operative position on the base member, locating means for automatically locating said supporting member in its operative position on the base member in two directions at right angles to one another at the end of its sliding movement into its operative position, which said holder can be adjusted on the supporting member in two directions lying transversely to one another and also angularly in its own plane in relation to the supporting member when said clamping means is slack but is still carried by said holder or said supporting member.

2. A press frame of the character described, comprising in combination a base member, a supporting member detachably mounted on the base member, a unit-holder for carrying a unit adjustably carried by said supporting member, clamping means for clamping said holder in its adjusted position on said supporting member, and holding means for removably securing the supporting member in its operative position on the base member, locating means for automatically locating said supporting member in its operative position on the base member in two directions at right angles to one another at the end of its sliding movement into its operative position, which clamping means slidably engage the said holder and its supporting member one in the direction of length of one of its sides, and the other in a direction lying transversely of the first said direction.

3. A press frame of the character described, comprising in combination a base member, a supporting member detachably mounted on the base member, a unit-holder for carrying a unit adjustably carried by said supporting member, clamping means for clamping said

holder in its adjusted position on said supporting member, and holding means for removably securing the supporting member in its operative position on the base member, locating means for automatically locating said supporting member in its operative position on the base member in two directions at right angles to one another at the end of its sliding movement into its operative position, which clamping means comprise a plurality of bolts carrying each a plate, which plates slidably engage each a lip on the sides of the supporting member, and the heads of which bolts are slidable each in a slot that is formed in said holder and extends at right-angles to the lips.

4. A press frame of the character described, comprising in combination a base member, a unit-holder supporting member in the form of an apertured frame member so carried thereby as to be slidable in its own plane into and out of its operative position thereon, locating means for automatically locating said supporting member in its operative position on the base member in two directions at right-angles to one another at the end of its sliding movement into its operative position, holding means for securing the supporting member on the base member in its located position, and a unit-holder in the form of an apertured frame member adjustably carried by said supporting member and registering therewith.

5. A press frame of the character described, comprising in combination a base member, a unit-holder supporting member carried thereby by two slideways, one at each lateral marginal portion of the base, so as to be slidable into and out of its operative position thereon, locating means situated between said slideways for automatically locating said supporting member in its operative position on the base member in two directions at right-angles to one another at the end of its sliding movement into its operative position, which locating means comprise a guide lying in one direction and a stop operative in the same direction, holding means for securing the supporting member on the base member in its located position, and a unit-holder adjustably carried by said supporting member.

6. A press frame of the character described, comprising in combination a base member, a unit-holder supporting member carried thereby by two slideways, one at each lateral marginal portion of the base, so as to be slidable into and out of its operative position thereon, locating means for automatically locating said supporting member in its operative position on the base member in two directions at right-angles to one another at the end of its sliding movement into its operative position, which locating means comprise stops in the form of grooves on one of

said members, tongues provided on the other of said members in the direction of sliding of the supporting member and arranged to enter said grooves, an undercut abutment on the base member, and a tapered stop on the supporting member for co-operating with said abutment and thereby arresting the supporting member at the end of its sliding movement into its operative position, holding means for securing the supporting member on the base member in its located position, and a unit-holder adjustably carried by said supporting member.

7. A press frame of the character described, comprising in combination a base member, a unit-holder supporting member so carried thereby as to be slideable into and out of its operative position thereon, locating means for automatically locating said supporting member in its operative position on the base member in two directions at right-angles to one another at the end of its sliding movement into its operative position, holding means in the form of a clamp for securing the supporting member on the base member in its located position, which clamp is arranged to press the supporting member in one direction in its own plane against said locating means and also simultaneously in a transverse direction against the adjacent face of the base member, and a unit-holder adjustably carried by said supporting member.

8. In a press frame of the character described, the combination with a supporting member in the form of a frame arranged to be slid by a tongue and groove engagement on to and off from a base member, a unit-holder also in the form of a frame slideable on said supporting member in two directions arranged face to face with the supporting member, which unit-holder is lying transversely one to the other and also adjustable angularly in its own plane in relation to the supporting member, and clamping means for clamping said holder in its adjusted position on the supporting member.

9. A press-frame of the character described, comprising in combination a base member and a unit-holder structure detachably and slidably mounted thereon, which said structure comprises two registering frame members one slideable on and adjustable angularly in its own plane in relation to the other, one of which frame members constitutes a holder for a unit and the other of said frame members constitutes a support for said holder on the base member, clamping means for clamping said holder in its adjusted position on the supporting frame member, holding means for removably securing the unit-holding structure in its operative position on the base member, and locating means for automatically locating said supporting frame of member in its operative position on

the base member in two directions at right-angles to one another at the end of its sliding movement into its operative position.

In testimony whereof I affix my signature.

ROBERT HARRIS.
